SLICE RECEIVING MECHANISM FOR RECIPROCATING CARRIAGE SLICING MACHINES

Charles L. Metzler, Palisades Park, N. J., assignor to Globe Slicing Machine Co. Inc., Stamford, Conn., a corporation of New York

Application April 4, 1944, Serial No. 529,505

10 Claims. (Cl. 146—94)

1

This invention relates to slicing machines in general and more especially to slicing machines of the type having a rotatable cutting knife mounted on a fixed shaft, an adjustable gauge plate disposed adjacent to the cutting area of the knife, and an object holder reciprocably mounted to move the object from the gauge plate to the cutting area of the knife and back again.

Among the objects of the present invention, it is aimed to provide an improved control mechanism for a slice receiving plate or tray that gradually descends as the slices are received thereon in combination with a slicing machine of the type aforesaid including anchoring means that are releasable when the plate or tray is manually lifted to return to its initial raised position.

Specifically, it is still a further object of the present invention to provide an improved mechanism for removably mounting the arm of the slice receiving tray whereby the same can be expeditiously removed to convert the machine for use when slicing objects such as cabbage and the like, and which removable means lends itself in turn to be readily re-assembled in position for gradually descending as slices are received on the tray.

Specifically, it is still another object of the present invention to provide a platform beneath the knife including a cover that can be raised to cover parts of the operating means that are ordinarily exposed when the slice receiving tray is in use, without in any way obstructing the platform for the reception of sliced substances, such as sliced cabbage, or for the reception of a colander or pan to receive sliced substances, such as sliced cabbage.

It is still another object of the present invention to provide another form of cam and cam control for the slice receiving tray.

These and other features, capabilities and advantages of the invention will appear from the subjoined detail description of specific embodiments thereof illustrated in the accompanying drawings in which

Figure 1 is a perspective of one embodiment looking at the machine from the rear.

Fig. 2 is a perspective on a smaller scale looking at the machine from the front.

Fig. 3 is a perspective similar to that illustrated in Fig. 2 with the slice receiving tray removed and the cover on the platform raised to cover parts of the operating mechanism that are ordinarily exposed when the slice receiving tray is used.

Fig. 4 is a transverse section on the line 4—4

2

of Fig. 5 of the machine on a scale larger than that illustrated in Fig. 1.

Fig. 5 is a fragmental plan of the machine illustrated in Fig. 4 with parts thereof shown in section.

Fig. 6 is a section on the line 6—6 of Fig. 5.

Fig. 7 is a front elevation of the machine with parts broken away and parts in section substantially on the line 7—7 of Fig. 4.

10 Fig. 8 is a fragmental front view substantially on the line 8—8 of Fig. 4.

Fig. 9 is a fragmental section on the line 9—9 of Fig. 7.

Fig. 10 is an enlarged fragmental section substantially on the line 10—10 of Fig. 7.

Fig. 11 is a section on the line 11—11 of Fig. 10.

Fig. 12 is a fragmental section on the line 12—12 of Fig. 10.

Fig. 13 is a section on the line 13—13 of Fig. 10.

20 Figs. 14 and 15 are front and side elevations, respectively, of the lower part of the hanger arm.

Fig. 16 is a fragmental end elevation partly in section enlarged of a modification.

25 Figs. 17 and 18 are fragmental plan views showing two positions respectively of the modification shown in Fig. 16.

Fig. 19 is a section on the line 19—19 of Fig. 16.

Fig. 20 is a fragmental section of still another embodiment.

30 Fig. 21 is an enlarged fragmental section on the line 21—21 of Fig. 20.

In the first embodiment shown, there is provided a frame 1 having side walls 2 and 3, a rear wall having an inclined portion 4 and an upright 35 wall 5 which is inclined slightly to the vertical. The wall 5 has a rounded connection 6 at the top continuing into its front wall portion 7 which is substantially parallel to the wall portion 5. Associated with the lower end of the wall 7 there is

40 provided a platform 8 which may be removably connected to the wall 7. This platform 8 has pivotally connected thereto the cover 9 which in descended position fits into the recess 10 formed in the platform 8 and assumes the position shown 45 in Fig. 2. In raised position, on the other hand, the cover 9 covers the opening 11 in the front wall 7 which is ordinarily exposed when the arm 12 and associated slice receiving tray 13 are operatively mounted. When the cover 9 is so raised, 50 however, as shown in Fig. 3, the arm 12 and associated slice receiving tray 13 are removed.

Motor and knife

To one end of the frame 1, and looking at the front of the machine, at the left hand end there-

of there are mounted and operatively associated the motor 14 and circular knife 15. The casing of the motor 14 is secured to the rear wall 5 so that the shaft 16 of the motor extends perpendicularly to and through the wall 5. The shaft 16 is journaled in the sleeve 17 which extends inwardly from the wall 5 and has an enlarged portion 18 in which is positioned the worm 19 in mesh with the worm wheel 20 mounted on the shaft 21 which has fixed on its lower end the sheave 22 which is connected by the belt 23 with the sheave 24 fixed to the knife 15 and rotatably mounted on the stub shaft 25 fixed in the bracket 26 extending from and secured to the front wall 7. In order to maintain the belt 23 in frictional driven and driving engagement with the sheaves 22 and 24, respectively, there is provided the idler 27 engaging the outer face of the belt 23 between the sheaves 22 and 24, the idler 27 being mounted on the lever 28 fulcrumed at 29 and having the arm 30 connected by the spring 31 to the abutment 32, the spring 31 resiliently urging the idler 27 into engagement with the belt 23, in turn to deflect the belt 23 and take up the slack in the same, thereby to maintain effective engagement of the belt 23 on the sheaves 22 and 24 in the well known manner.

The axis of the stub shaft 25 is substantially parallel to the wall 7 which in the present instance forms an angle of about thirty degrees to the vertical. This inclination is provided to conform to the gravity feed of the object holder hereinafter to be described. It is, of course, obvious that this gravity feed can be obtained when the angle to the vertical departs from thirty degrees. However, since excellent results have been obtained when the inclination approaches thirty degrees, the disclosure here, of course, is to be considered only as one embodiment of this invention. The bracket 26 in the present instance is provided with a bell or dish shaped portion 33 having a shoulder 34 to receive the plate 35 which extends adjacent to the lower face of the disk portion 36 of the knife 15 and then is connected at its rear end to the upper portion of the bracket 26 by suitable fastening means such as the screws 37. This plate 35 has a central opening that just clears the sheave 24 adjacent to the lower face of the disk portion 36. The cutting edge of the knife 15 is formed at the outer edge of the cone shaped portion 38 of the knife blade 15 which cone shaped portion 38 in turn has a shoulder 39 which is disposed adjacent to the disk 40 secured to the bracket 41 which in turn is secured to the upper end of the stub shaft 25. The plates 35 and 40 cooperate to prevent the entrance of food particles or particles of the object being sliced to the belt 23 and associated operating parts.

Also extending from and being secured to the wall 7 there is provided the guard 42 which has a flange 43 resting on the bracket 26, and another flange 44 covering the cutting edge of the blade 15 for substantially two hundred seventy degrees, leaving the cutting edge of the knife 15 only exposed in the cutting area, that is, between the ends 45 and 46 of the guard 42. The guard 42 also has an outer extension 47 to receive the sharpening mechanism 48 pivotally connected at 49 to the bracket 50 secured to the outer portion 51 of the bracket 26.

Gauge plate

Arranged in accordance with accepted practice, to the right hand side of the knife 15 there is provided the gauge plate 52. This gauge plate, 75

see Figs. 7, 9 and 10, is fixed to the arm 53, which in turn is fixed to the bearing 54 slidably mounted on the rod 55. The rod 55 is disposed inside of the frame between the walls 5 and 7 and the axis of the rod 55 is substantially parallel to the walls 7 and 5. Extending to the right of the bearing 54 is provided the arm 56 which has a slot to receive the guide plate 57 secured to the partition 58 integral with the front wall 7 of the frame.

The bearing 54, see Fig. 10, also has secured to the rear thereof the bracket 59 having fixed thereon the cam 60 shown in front elevation in Fig. 7. The bracket 53 in turn is provided with a slot 61 extending at right angles to the axis of the rod 55 to receive the pin 62 at the end of the arm 63 fixed to the mutilated worm wheel 64 journaled on the pin 65. The upper face of the gauge plate 52, in accordance with practice, is parallel to the cutting edge of the knife 15 adjustable to different levels according to the thickness of slice to be cut. The mutilated worm wheel 64 is rotatable in turn to determine the level of the gauge plate 52. In the present instance the cam 60 associated with the gauge plate 52 will be adjusted simultaneously with the level adjustment of the gauge plate 52 by the rotation of the mutilated worm wheel 64. Since the cam 60 controls the successive degree of descent of the slice receiving tray 66, hereinafter to be described, the actuation of the mutilated worm wheel 64 will constitute a common adjustment for the two.

Object holder

In accordance with this type of machine, there is reciprocably mounted across the gauge plate 52, and into slicing engagement with the knife 15, a carrier known as an object holder 67. This object holder in the present instance has two wings 68 and 69 forming a dihedral angle with one another and extending substantially perpendicular to the upper face of the gauge plate 52. The wings 68 and 69 are secured to the arm 70 which in turn is provided with an extension 71 secured to the hanger 72 and having a sleeve 73 slidably mounted on the horizontally extending rod 74. The hanger 72, see particularly Fig. 7, has a goose neck 75 to clear the belt 23 and associated drive connection between the knife 15 and motor 14 when the hanger is advanced to the left hand end of the machine as indicated by the dot and dash line position of the goose neck 75 in Fig. 7. The lower end of the hanger 72 is provided with the extension 76 mounted in the sleeve 77 of the sleeve 77 slidably mounted on the rod 78 parallel to the rod 74. The left hand ends of the rods 74 and 78 are connected to the end wall 3 of the frame. The right hand end of the rod 78 is connected to the wall 2. The right hand end of the rod 74, on the other hand, is connected to the partition part 79 of the web 58 (Fig. 7) parallel to the wall 2 and extending down from the curved upper wall portion 6 of the frame. Preferably as shown in Figure 1, the arm 70 has an extension 80 having a handle 81 secured thereto, the extension 80 extending to the right of the arm 70 and the handle 81 extending to the rear of the extension 80.

In accordance with custom, one of the wings 68, 69, the wing 68 in the present instance, is provided with a guide rod 82 to receive the sleeve 83 for the weighted arm 84 which engages the upper face of the object being supported by the object holder 67.

The arm 70 preferably is secured to the wings 68

and 69 for ready removal. In the present instance the connection used consists primarily in a seat 170 (Fig. 5) to receive the end 171 of the bracket 172 fixed to the rear end of the wings 68 and 69. The end 171 and seat 170 have registering openings to receive the sleeve 173 on the rod 174. The sleeve 173 has an enlargement 175 to engage the inner end of the end 171 of the bracket 172 when the bracket 172 is positioned as shown in Fig. 5 to hold the wings 68 and 69 above the gauge plate 52. The opening in the seat 170 is elongated and receives the sleeve 173 to position the same. The opening in the end 171 is similarly slotted to enable the bracket 172 to be removed upwardly out of engagement with the seat 170 in turn to remove the wings 68 and 69 for cleaning or the like.

The rod 174 extends through the web 176 between which and the sleeve 173 is positioned a spring 178 normally to urge the sleeve 173 outward. The rod 174 is screw threadedly connected to the nut 179. This rod extends through and is connected to the head 180 protruding from the rear end of the arm 70. This head 180 preferably has a finger piece 181 secured thereto to facilitate turning the head 180. The nut 179 is anchored against rotation in the enlargement 175 so that when the head 180 is turned it will make it possible when pressure is applied to the head 180 to free the end 171 from the seat 170 and enable the wings 68 and 69 to be raised out of engagement with the seat 170. In turn, by this connection, it is possible to adjust the position of the object holder 67 a predetermined distance above the gauge plate 52. When it is desired again to lock the wings 68 and 69 in object holding position, it is only necessary to turn the head 180 and exercise sufficient pressure to enable the end 171 to slide down over the sleeve 173 between the enlargement 175 and the seat 170, and then when the desired position has been located to turn the head 180 until the end 171 is securely anchored in position. In some cases where the attendant desires to slice an object without the use of the object holder, he places the object adjacent to the guiding bracket 182 formed on the gauge plate 52, see Fig. 10. This shoulder forming bracket, see Fig. 5, has its outer face registering with the end 46 of the guard 42.

The bracket 172 has an upper wall 282 which cooperates with the pin 183 in the enlargement 175 to locate the object holder 67 in its normal lowermost position, that shown in Fig. 4.

Slice receiving tray

The slice receiving tray 66 is adapted to be removably connected to the hanger 72 so that in some instances the space under the knife is left free to allow the object being sliced, such as cabbage, to drop directly onto the platform 8 or else into a dish or colander supported on the platform 8.

On the other hand, when the tray 66 is operatively associated with the hanger 72, then by the mechanism now to be described it will descend with each slicing operation a distance substantially corresponding to the thickness of slice being cut.

In order to operatively associate the tray 66 with the hanger 72, there is provided an arm or bracket portion movably connected but otherwise ordinarily permanently connected to the hanger 72, which bracket portion includes the bifurcated bracket 85 shown in Fig. 13. For this operative association there is also provided a second

bracket or arm portion more or less permanently connected to the tray 66 but removably associated with the bracket 85. As an instance, the tubular member 86, see Fig. 13.

The bracket 85 is provided with two journals 87 and 88 to receive the shaft 89 which extends through the journals 90 and 91 at the ends of the arms 92 and 93, extending down from the extension 193 of the hanger 72. The arm 92 is provided with a stop arm 94 positioned above the journal 87 and opposite to the stop arm 95 on the bracket 85. Below the journal 87 the arm 92 has a stop arm 96 opposite to the stop arm 97 formed on the bracket 85. The arm 93 has two sleeves 98 and 99 to receive the rod 100, having a cam roller 101 at its upper end and an extension or finger 102 at its lower end connected by the spring 103 to the extension 193 normally to urge the cam roller 101 upwardly in position to cooperate with the cam 60. The rod 100 is provided with a recess 104 to receive the pin 105 at the end of the arm 106 mounted on the shoulder of the friction drive collar 107, rotatably mounted in the extension 108 of the shaft 109 which is journaled in the bearing 110 formed in the extension 193. The extension 108 has a sleeve portion 111 between which and the cam face 112 of the drive member 107 there is nested a friction drive roller 113. The shaft 109 in the present instance is pinned to the worm 114 in mesh with the worm wheel 115 fixed on the shaft 89.

The journals 87 and 88 of the bracket 85 are rotatably mounted on the shaft 89. However, to anchor the bracket 85 to rotate with the shaft 89, there is provided the ratchet wheel 116, also fixed to rotate with the shaft 89. The bracket 85, on the other hand, has mounted on the side thereof the stub shaft 117 on which are mounted the pawls 118 and 119 to cooperate with the ratchet wheel 116. The pawl 119 is provided with an extension or finger 120 and the pawl 118 is provided with a pin 121 to be engaged by the pawl 119 to raise it out of engagement with the ratchet 116 when the finger 120 is raised to clear the pawls 118 and 119 from the ratchet wheel 116. Resiliently to maintain the pawls 118 or 119 in engagement with a tooth of the ratchet wheel 116, there is provided the spring 122 connecting the stub shaft 117 with the pawl 118 as shown in Fig. 4. From the foregoing it will thus be seen that as a result of the cooperation between the cam 60 and cam roller 101, the rod 100 will be actuated in turn to actuate the arm 106 and through the ball clutch 113 actuate the sleeve 111 and thereby the shaft 109 in turn through the worm 114 and worm wheel 115 to actuate the shaft 89 and this shaft 89 in turn through the ratchet wheel 116 and pawls 118 or 119 actuate the bracket 85. This actuation is intermittent as the hanger with the receiving tray 66 is reciprocated to and fro into and out of the cutting area and simultaneously into and out of cam 60 engaging position with the cam roller 101 in turn to effect the gradual descent of the tray 66 to correspond with the successive slices being received.

The bracket 85 and tubular housing 86 constitute parts of a pantographic device relying upon the well known parallelogram control mechanisms. For this purpose the arms 123 and 124 of the hanger 72 extending down below the bearings 90 and 91 are formed into bearings 125 and 126 for receiving the shaft 127 which has fixed thereto and extending at right angles thereto the enlargement 128 which is connected to the

rod 129. At the free end of the bracket 85 there is formed an enlargement 130 having a large tubular opening 131 to receive the key way thimble 132 and is also provided with a smaller opening 133, see Fig. 10, flaring outwardly in either direction, with the end of the rod 129 extending part way into the opening 133. The tubular member 86 has secured at one end the guide piece 134 for the rod 135 and adjacent the other end is provided with a disk 136 secured in position by the depressed lip 137. The disk 136 has a central opening therein through which the rod 135 extends, the outer end of the rod having fixed thereto the handle 138 adjacent to which is provided the collar 139 slidably mounted in the tubular member 86 and between which collar 139 and disk 136 there is positioned a spring 140 to normally maintain the handle 138 in its outermost position determined by the cross piece 141 which will either engage the outer end of the guide piece 134 or engage the outer face of the key way thimble 132. The key way thimble, see Fig. 11, is provided with a transverse slot 142 to clear the cross piece 141 and permit it to slide through the thimble 132 when the cross piece 141 registers with the slot 142. On the other hand, the outer face 143 of the thimble 132 is inclined or cammed to enable the cross piece 141 readily to ride up on the same and into the recess 144. When the cross piece 141, as shown in Fig. 11, rests in the recess 144, the spring 140 will yieldably maintain the same in such recess and at the same time urge the handle 138 outwardly as shown in Fig. 10. The outer end of the tubular member 86 is fixed in the sleeve 145 secured to the crosshead 146 pivotally connected at its ends on the trunnions 147 and 148 secured to the cheeks 149 and 150 extending downwardly from the slice receiving tray 66. Below the trunnions 147 and 148 there is pivotally connected the rod 151 to the inner faces of the cheek plates 149 and 150. This rod 151 in turn is secured to the sleeve 152 screw threadedly connected to the rod 153. The rod 153 is provided with a guide 154 which forms part of the bracket 155 secured to the tubular member 86. Surrounding the rod 153 and secured at one end to the guide 154 is the tubular member 156 having a shoulder 157 at its outer end between which and the disk 158 on the rod 153 there is compressed the spring 159, thereby tending to urge the rod 153 outwardly so that its outer end 160 when located in the opening 133 will engage the free end of the rod 129. By this arrangement, it will appear that the pantographic device, formed on the parallelogram principle, operates about the shafts 146, 151, 127 and 89 to maintain the slice receiving tray 66 in a predetermined position substantially horizontal but preferably slightly inclined as shown in Fig. 10. To limit the movement of the rod 153 relative to the tubular member 156 there are, in the present instances, provided the stop nuts 185 and 187.

When it is desired to separate the tray 66 and arm 66 from the bracket 85, and thus clear the space beneath the knife and gauge plate so that the sliced material can either drop directly on to the platform 8 or on to a dish positioned on the platform 8, it is only necessary to grasp the handle 138 and turn it to cause the key 141 to be turned at right angles to register with the key way 142 in the plug 132, thereby compressing the spring 140, and then withdraw the arm 86 with the tray 66. Thereupon in order to conceal the operating parts of the hanger 72, the cover 9

may be raised into the position shown in Fig. 3 and the platform used either to receive the sliced material or to support a dish for receiving the sliced material.

5 While not necessary in every instance, in some instances it may be desirable to remove the platform 8 and its associated cover 9. For this reason the platform 8 and cover 9 are removably connected to the frame 1 by a yieldable connection such as the connection 161 shown in Fig. 4.

15 On the other hand, when the slice receiving tray 66 is secured to the bracket 85, as shown in Fig. 4, it will gradually descend in a step by step manner with each slicing operation to make room for the succeeding slices as they are received. When the order has been filled and it is then desirable to return the slice receiving tray 66 to its normal raised position for a fresh order, it is only necessary for the attendant to touch the lower portion of the plate 66 with his finger and raise it when the pawl mechanism 118, 119 and 120 will idle across the ratchet teeth of the ratchet wheel 116 without disturbing the position of the shaft 89.

20 25 Common adjustment for gauge plate and slice receiving tray

The knurled knob 162, see Figs. 1 and 7, is provided with graduations 163 to register with the notch 164 in the end wall 2 adjacent the rounded wall portion 6, see Figure 1, to control the adjustment of the gauge plate 52 and the step by step descent of the slice receiving tray 66. This knob 162 is fixed to the hub of the gear 166 rotatably mounted on the shaft 165 which is an extension of bar 14. The gear 166 meshes with the gear 167 fixed on the shaft 168 journalled in the wall 2 and partition 58 and having secured thereon the worm 169 in mesh with the worm wheel segment 64.

40 45 From the foregoing it will thus appear that depending upon the position of the knob 162, the bracket 54 will be positioned through the pin 62 and slot 61, thereby in turn to position not only the gauge plate 52, but also the cam 60.

50 55 Subsequently, in the operation of the machine after raising the slice receiving tray 66 to its initial top position, and the object to be sliced is positioned on the gauge plate 52 and by the object holder 67, the ensuing reciprocation of the object holder 67 will cause the object to be sliced when it reaches the cutting edge of the knife 15, and in turn as the roller 101 strikes the advance edge 601 of the cam it will cause the rod 100 to be depressed in turn to actuate the pin 104 and thereby the arm 106 in turn to engage the drive roller 113 to cooperate with and rotate the driver member 108 and thereby the shaft 109 in turn to actuate the worm wheel 115 by the worm 114 and through the ratchet wheel 116 and anchor to the bracket 85 by the pawl or ratchet mechanism 118, 119 and 120 cause the bracket 85 to receive a descending actuation. The high spot 602 of the cam 60, see Fig. 5, is positioned with respect to the cutting field of the knife 15 so that it will be engaged by the roller 101 shortly after a small cut has been effected. The cam 60 has a second cam face 603 to be engaged by the roller 101 upon the return stroke or return movement of the object holder 67. In this way the present invention relies upon two cam actions to cause the slice receiving tray 66 to descend a distance corresponding to the thickness of a single slice, half the distance being negotiated when the roller 101 engages the cam face 601, and the other half

of descent being negotiated when the roller 101 engages the cam face 603 on the return movement.

When the cam is so positioned, the descent of the slice receiving tray 66 can be effected when the object holder 67 is moved back and forth a comparatively short distance, just sufficient to enable the roller 101 to be fully actuated by the cam face 601 in one direction and by the cam face 603 in the other direction. In the operation of the machine, a decided advantage is achieved by this arrangement when, for instance, the object to be sliced is a bologna of comparatively small diameter.

In order to determine the uppermost limit of motion of the gauge plate 52, there is provided the stop 184 secured in the enlargement 185 extending downwardly from the rounded portion 6 of the frame to serve as an abutment for the upper face of the arm 56.

In the modification shown in Figs. 16, 17, 18 and 19, there is provided an improved adjustable arm 188 instead of the arm 70 of the embodiment shown in Fig. 1.

The wings 189 and 190 of the object holder are fixed to the bracket 191 which in turn has a tapered rear end portion 192 provided with a threaded stud or pin 293. The end portion 192 is conformed to fit in the seat provided by the webs 194 and 195 of the bracket 196 having a vertical slot 197 to receive the pin 293. On the pin 293 there is threadedly secured the clamping nut 198 for anchoring the end 192 and therewith the wings 189 and 190 on the bracket 196. The slot 197 obviously may cooperate with the pin 293 and nut 198 for vertical adjustment of the wings 189 and 190 relative to the gauge plate, here numbered 199. In order to facilitate this vertical adjustment, the set screw 218 is provided at the bottom of the slot 197 to form an abutment for the stud 293.

The bracket 196 in turn is provided with an arm portion 200 slidably mounted on the arm portion 201 secured to the hanger 202. In order to provide proper alignment, the arm portion 201 is provided with raised portions 203 and 204 riding in the slot 205 of the arm portion 200.

The arm portion 200 may be located at various positions on the arm portion 201 and thereby position the wings 189 and 190 relative to the cutting area or cutting field of the knife, not shown in Figs. 16, 17 and 18.

The value of this adjustment is immeasurable, particularly when the machine is being used with a slice receiving tray such as the tray 13. As an instance, after the attendant has finished an order requiring slices to be cut from a fairly bulky object, such as a ham, and the object holder is positioned as shown in Fig. 4, and he is then required to slice an article of smaller diameter such as a bologna of less than two inches in diameter, unless the object holder is adjusted the slices as they are cut would drop on the edge of the tray 13 adjacent the wall 7 and not infrequently slip off. If, on the other hand, the attendant is enabled to adjust the position of the object holder, that is, position the wings 189 and 190 further downward in some cases into the position shown in Fig. 18 when he desires to slice an object of a small diameter, such as a bologna, he can, of course, insure himself that the slices when liberated will be definitely deposited on the tray 13.

The adjustment mechanism may partake of various well known forms. In the present instance the mechanism illustrated consists essen-

tially of an upright pin 206 to which is secured the disk 207 rotatably mounted in the recess 208 of the arm portion 201. This pin 206 extends upwardly through the elongated slot 209 in the arm portion 200 and is provided with a loosely mounted disk 210 resting on the upper surface of the arm portion 200. The upper end of the pin 206, see Fig. 19, is pivotally connected to the cam disk 211 to which is secured the lever 212. The lower end of the pin 206 on the other hand extends down below the lower face of the arm portion 201 and has secured thereto the two stop nuts 213 and 214 immediately below the washer 215 disposed to engage the lower face of the arm portion 201.

In addition to the elongated slot 209 extending throughout the thickness of the arm portion 200, there is also provided the shallow recess 216, in the present instance shown as extending at right angles to the slot 209 and positioned to receive the projection or lug 217 secured to and extending upwardly from the disk 207.

In operation, when the lever 212 is depressed and in the position shown in Fig. 17, the lug 217 will position the arm portion 200 inwardly, that is, with the wings 189 and 190 in the position nearest to the hanger 202. In the position shown in Fig. 18, on the other hand, the lug 217 will position the arm portion 201 in its outermost position. Obviously the lever 212 may be anchored at any intermediate position between the two extreme positions shown in Figs. 17 and 18. Obviously, too, by raising the lever 212 it will free the disks 210 and 215 from engagement with the outer faces of the arm portions 200 and 201, respectively, and facilitate turning the pin 206 with its disk 207 in turn to cause the lug 217 to move the upper arm portion 200 to or from the hanger 202.

In the modification shown in Figs. 20 and 21 there is provided another construction for carrying the cam 219 in place of the cam 60 of the embodiment illustrated in Fig. 7. This cam 219 is provided to cooperate with the cam roller 220 substantially identical to the cam roller 101 of the embodiment illustrated in Fig. 7. The cam 219 in this embodiment is secured to the lever 220 provided with the pin 221 journalled in the boss 222. The boss 222 in the present instance is integral with the boss 223, see Fig. 10, secured to the wall 7 and forming an abutment for the lower end of the post or rod 55. One end of the lever 220 adjacent to its pivot pin 221 is provided with a gear segment 224 to mesh with the worm 225 on the shaft 226. The shaft 226 has fixed thereon in the present instance the worm 227 identical to the worm 169 of the embodiment illustrated in Fig. 7.

When a hanger is provided with a cam roller, such as the cam roller 101 of the mechanism of the embodiment of Fig. 7 for controlling the gradual descent of a slice receiving tray, the cam with which it cooperates must be stationary relative to the reciprocal movement of the hanger. Obviously various cam constructions can be contrived without departing from the general spirit of the invention. As an instance, the cam construction illustrated in the patent of John Jacob Waage, 2,381,016, dated August 7, 1945, where the cam is disposed below the cam roller, is indicative of another cam construction. In the present application this is a second embodiment showing a construction where the cam, as an instance the cam 219, is disposed above the cam roller, as an instance the cam roller 220.

It is obvious that various changes and modi-

fications may be made to the details of construction without departing from the general spirit of the invention as set forth in the appended claims.

I claim:

1. The combination of a frame having a housing, a platform extending forwardly from the lower end of said housing, a bracket extending forwardly from said housing and spaced from and above said platform, a rotatable knife mounted on said bracket and forming substantially a right angle between its cutting plane and said housing, a gauge plate extending forwardly from said housing and registering with the cutting plane of said knife, said housing having a front wall with an opening therein, a hanger reciprocably mounted in said housing, a slice receiving tray, a device for removably connecting said tray to said hanger and normally extending through the opening in said front wall, and a cover hingedly connected to said platform to swing upwardly and close the opening in said front wall when said slice receiving tray has been removed.

2. The combination of a frame, a knife operatively mounted on said frame, a hanger movably mounted on said frame, an object holder on said hanger to be actuated with said hanger into and out of cutting relation with said knife, a bracket pivotally connected to said hanger, a step by step control mechanism mounted on said hanger, means for anchoring said bracket to said control mechanism effective to lower said bracket a predetermined slice thickness distance with each reciprocation of said hanger, and a slice receiving tray having an arm operatively connected to said bracket, said anchoring means including a pawl and ratchet mechanism and being releasable when said tray and arm are manually lifted to return said tray and arm to its initial raised position and turned about the axis of the ratchet.

3. The combination of a frame, a knife operatively mounted on said frame, a hanger reciprocably mounted on said frame, an object holder associated with said hanger to be moved into and out of cutting relation with said knife by the reciprocation of said hanger, a bracket on said hanger pivotally mounted below said object holder, an arm connected to said bracket, a slice receiving tray on the free end of said arm, a control mechanism for lowering said bracket and therewith said tray a predetermined slice thickness distance with each reciprocation of said hanger, said control mechanism including a rotatable shaft, a ratchet wheel fixed on said shaft, and a ratchet mechanism for releasably anchoring said bracket to said ratchet wheel to be returned to initial position when turned about said ratchet wheel.

4. The combination of a frame, a knife operatively mounted on said frame, a hanger reciprocably mounted on said frame, an object holder connected to said hanger to be moved into and out of cutting relation with said knife upon the reciprocation of said hanger, a slice receiving tray, a pantographic device operatively connecting said hanger to said tray to maintain said tray in a predetermined substantially horizontal position while being moved relative to said hanger, a step by step control mechanism mounted on said hanger to be actuated a predetermined distance with each reciprocation corresponding to a predetermined slice thickness, a mechanism for removably anchoring said pantographic device to said control mechanism, and a pawl and ratchet mechanism for releasably connecting said pantographic device to said control mechanism to enable said tray to be manually lifted to initial

raised position when being turned about the axis of the ratchet.

5. The combination of a frame, a knife operatively mounted on said frame, a hanger reciprocably mounted on said frame, an object holder connected to said hanger to be moved into and out of cutting relation with said knife upon the reciprocation of said hanger, a slice receiving tray, a pantographic device operatively connecting said hanger to said tray to maintain said tray in a predetermined substantially horizontal position while being moved relative to said hanger, a step by step control mechanism mounted on said hanger to be actuated a predetermined distance with each reciprocation corresponding to a predetermined slice thickness, and a mechanism for removably anchoring said pantographic device to said control mechanism, said pantographic device including two parallel rod elements pivotally connected at one of their ends to said hanger and pivotally connected at their other ends to said tray.

6. The combination of a frame, a knife operatively mounted on said frame, a hanger reciprocably mounted on said frame, an object holder connected to said hanger to be moved into and out of cutting relation with said knife upon the reciprocation of said hanger, a slice receiving tray, a pantographic device operatively connecting said hanger to said tray to maintain said tray in a predetermined substantially horizontal position while being moved relative to said hanger, a step by step control mechanism mounted on said hanger to be actuated a predetermined distance with each reciprocation corresponding to a predetermined slice thickness, said pantographic device including a first bracket pivotally connected to said hanger, a rod having one end slidably in said first bracket and its other end pivotally connected to said hanger, a second bracket fixed to said tray, a pair of rods pivotally connected to said second bracket and slidably connected to said second bracket with one of said rods abutting against the free end of the rod pivotally connected to said hanger, and a mechanism for releasably anchoring said first bracket to said control mechanism.

7. The combination of a frame, a knife operatively mounted on said frame, a hanger reciprocably mounted on said frame, an object holder mounted on said hanger to be actuated into and out of cutting relation to said knife with the reciprocation of said hanger, a first bracket pivotally connected to said hanger, a second bracket, a slice receiving tray mounted at the free end of said second bracket, control mechanism on said hanger actuatable with each reciprocation of said hanger, a pawl and ratchet mechanism for releasably connecting said first bracket to said control mechanism to enable returning said first bracket and therewith said tray to initial raised position by turning said first bracket about the axis of the ratchet, and means for removably connecting said second bracket to said first bracket.

8. The combination of a frame, a knife operatively mounted on said frame, a hanger reciprocably mounted on said frame, an object holder mounted on said hanger to be actuated into and out of cutting relation to said knife with the reciprocation of said hanger, a first bracket pivotally connected to said hanger, a second bracket, a slice receiving tray mounted at the free end of said second bracket, control mechanism on said hanger actuatable with each reciprocation of said

hanger, mechanism for releasably connecting said first bracket to said control mechanism, and means for removably connecting said second bracket to said first bracket, said removable connecting means including a key way in said first bracket, a spring pressed rod slidably mounted in said second bracket and having a key cooperating with the key way in said first bracket.

9. The combination of a frame, a knife operatively mounted on said frame, a hanger reciprocably mounted on said frame, an object holder mounted on said hanger to be moved into and out of cutting relation to said knife with the reciprocation of said hanger, an arm pivotally connected to said hanger, a slice receiving tray mounted on the free end of said arm, a control mechanism mounted on said hanger to be actuated a distance corresponding to a slice thickness with each reciprocation of said hanger, said control mechanism including a first shaft, a worm fixed on said first shaft, a friction drive operatively associated with said first shaft actuatable with each reciprocation of said hanger, a second shaft, a worm wheel fixed on said second shaft in mesh with said worm, a ratchet wheel fixed on said second shaft, and a ratchet mechanism for releasably anchoring said arm to said ratchet wheel.

10. The combination of a frame having a housing, a platform extending forwardly from the lower end of said housing and the full length of said housing, a bracket extending forwardly from said housing and spaced from and above said platform to insure a clearance above the platform, a rotatable knife mounted on said bracket and forming substantially a right angle between its cutting plane and said housing, a hanger reciprocably mounted in said housing, there being an

opening in the rear face of said housing, an arm extending from said hanger through said opening and over to the front face of said housing, an object holder mounted on the free end of said arm in position to be moved into and out of cutting relation to said knife but spaced from said platform to insure a clearance above the same, a gauge plate extending forwardly from said housing and registering with the cutting plane of said knife but spaced from the platform to insure a clearance above the same, said housing having a front wall with an opening therein, a slice receiving tray, a device for removably connecting said tray to said hanger and normally extending through the opening in said front wall to travel in the clearance above said platform, and a cover hingedly connected to said platform to swing upwardly and close the opening in said front wall when said slice receiving tray has been removed but preserving the clearance above said platform, the clearance above said platform enabling the use of a dish of any desirable length to receive the cut portions when the slice receiving tray has been removed.
